UNITED STATES PATENT OFFICE.

HENRY TARDIFF, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed February 29, 1924. Serial No. 695,876.

My invention relates to drilling mechanisms.

It has for its object to provide an improved drilling mechanism. Another object is to provide an improved hole cleansing means. A further object is to provide improved hole cleansing control means in a drilling mechanism employing a fluid distributing valve. Another object is to provide improved means for controlling the movement of the fluid distributing valve to cleanse the hole being drilled. A further object is to provide improved manually operable means for holding the fluid distribution valve at one end of its stroke in order to direct live pressure fluid to only one end of the hammer piston from which fluid might flow through a hollow steel and thereby cleanse the hole. Another object is to provide improved manually operable cam means for accomplishing the above function.

In the accompanying drawings I have shown for purposes of illustration one form which my invention may assume in practice.

25 In these drawings,

Fig. 1 is a vertical longitudinal section through my improved drilling mechanism, parts of which are shown in elevation.

Fig. 2 is a fragmentary plan view of the 30 fluid distributing valve mechanism.

In the illustrative form of my invention I have shown the same embodied within a drilling mechanism comprising a usual cylinder 1 having a piston 2 reciprocably mounted therein and projecting forwardly from which is a striking bar 3 having flutes 4 adapted to cooperate with lugs in a chuck nut 5. Any suitable ratchet and rifle bar mechanism, not shown, may be carried in the rear head 7 to cause rotation of the piston 2 and also of a chuck sleeve 8 which carries the chuck nut 5, this sleeve being rotatably mounted within a chuck housing 9 carried on the front end of the cylinder. 40 Also carried by the rear head are usual hole cleansing fluid conducting tubes 10 one of which terminates within the hollow steel 11 carried in the sleeve 8. Live actuating fluid is controlled by a usual manually operable valve 12 carried in the rear head 7 and adapted to control the flow of live pressure fluid to an automatic fluid distributing valve 13 reciprocably mounted within a valve housing 14 formed on the side of the cylinder 50 1 and adapted to control flow of live fluid

to, and exhaust fluid from, the cylinder through passages 15. The valve structure is held together by side rods 16 connected at opposite ends by a spring 17 which holds valve buffers 18 in position.

It is sometimes desired to supply supplemental hole cleansing fluid to the hollow steel 11 and the same is accomplished by providing suitable means for holding the piston 2 in its rearward position, in which case live pressure fluid in the front end of the cylinder will flow along the flutes 4 and through the clearance between said flutes and the nut 5 to the hollow steel 11. To hold the piston in such position, I have provided a 60 novel means for throwing the valve 13 to its rearward position in which case live pressure fluid will be continuously admitted to the front end of the cylinder. This improved throwing means comprises a fluted stem 20 65 longitudinally movable in a bore 21 which extends rearwardly from an enlarged bore 22 both of which are formed within one of the buffer members 18. Disposed within the enlarged bore 22 and carried by the stem 20 70 is an enlarged head 23 from which a stem 24 projects outwardly through a hole 25 formed in one of the cross springs 17. It is to be noted that the head 23 is also fluted so that the rear end of the valve 13 is vented to 75 the atmosphere. Suitable means are provided for shifting the valve as by forcing the stem 24 inwardly and which comprises a grasping lever 26 pivotally mounted upon one of the side rods 16 which is slightly 80 longer than the other one which grasping lever carries on its inner end a cam member 27 having an inclined cam surface 28 adapted when moved upwardly to engage the stem 24 and thereby thrust the same inwardly to 85 hold the valve 13 in inoperative position. It will herein be noted that when the valve 13 is held in its inoperative position as shown in Fig. 1 pressure fluid flows from the fluid supply passage past the right hand side of 90 the central spool of the valve and through the right hand distributing passage 15 to the forward end of the cylinder, thus causing the piston to be held in its extreme rearward position, motive fluid then passing through 95 the flutes 4 in the striking bar 3 of the piston and thence through the hollow drill steel to cleanse the drill hole. Upon downward movement of said cam, the valve and motor piston will resume their normal operation.

It will thus be seen that I have provided an extremely simple means for actuating the valve and one which requires very little exertion on the part of the operator.

6 While I have in this application specifically described one form which my invention may assume in practice, it will be understood that this form of the same is shown for purposes of illustration and that the invention may be modified and embodied in various other forms without departing from its spirit or the scope of the appended claims.

15 What I claim as new and desire to secure by Letters Patent is:

1. The combination with a drilling mechanism having a valve mechanism including an automatic fluid distributing valve, side rods for holding parts of said valve mechanism in assembled relation, of hole cleansing means including control means therefor comprising a member pivotally connected to one of said side rods and provided with means for controlling said valve.

25 2. The combination with a drilling mechanism having a valve mechanism including an automatic fluid distributing valve and side rods for holding parts of said valve mechanism in assembled relation, of hole cleansing means including control means comprising a lever pivotally connected to one of said side rods and having a cam portion formed thereon for actuating said valve.

30 3. The combination with a drilling mechanism having a valve mechanism including an automatic fluid distributing valve, side rods for holding parts of said valve mechanism in assembled relation, and a stem engageable with said valve for varying the 40 operation thereof, of hole cleansing means

including control means comprising a manually operable cam member pivotally connected to one of said side rods and in slidable engagement with said stem for actuating said stem.

45

4. The combination with a drilling mechanism having a valve mechanism including an automatic fluid distributing valve, side rods for holding parts of said valve mechanism in assembled relation and a stem engageable with said valve for varying the operation thereof, of hole cleansing means including control means comprising a cam member pivoted on one of said side rods and movable transversely of said valve in engagement with said stem for actuating said valve.

55

5. The combination with a drilling mechanism having a valve mechanism including an automatic fluid distributing valve, side rods for holding parts of said valve mechanism in assembled relation and a stem engageable with said valve for varying the operation thereof, of hole cleansing means including control means comprising a transversely movable cam member pivoted on one of said side rods for actuating said stem, and a laterally projecting operating element for said cam member.

60

6. The combination with a drilling mechanism having an automatic reciprocable fluid distributing valve, of hole cleansing means including control means for said valve comprising a cam lever pivoted on an axis parallel to the line of reciprocation of said valve, said lever being swingable in a plane extending transversely of the longitudinal axis of said valve and having a cam surface thereon for actuating said valve.

65

In testimony whereof I affix my signature.
HENRY TARDIFF.
